UNITED STATES PATENT OFFICE.

BLANCHE M. BURR, OF SOUTH FRAMINGHAM, MASSACHUSETTS.

GARMENT-FASTENER.

SPECIFICATION forming part of Letters Patent No. 758,507, dated April 26, 1904.

Application filed September 30, 1903. Serial No. 175,198. (No model.)

To all whom it may concern:

Be it known that I, BLANCHE M. BURR, a citizen of the United States, residing at South Framingham, in the county of Middlesex and State of Massachusetts, have invented new and useful Improvements in Garment-Fasteners, of which the following is a specification.

My invention relates to new and useful improvements in garment-fasteners; and its object is to provide a simple, inexpensive, and artistic device of this character which is especially adapted for securing dress-shields in position or for any other desired purposes.

With the above and other objects in view the invention consists in providing a length of spring metal having a hooked end provided with a head, and extending from this end is an engaging portion, preferably formed of one or more coils and the tapered end of said portion being inclosed by the coils. These coils may be of any suitable form.

The invention also consists in the further novel construction and combination of parts hereinafter more fully described and claimed, and illustrated in the accompanying drawings, showing the preferred form of my invention, and in which—

Figures 1, 2, 3, and 4 are elevations of different forms of fasteners constructed in accordance with my invention, and Fig. 5 is an elevation showing the dress-shield secured in position by fasteners constructed in accordance with my invention.

Referring to the figures by numerals of reference, 1 is a hook having a head 2 at its free end, while a strip 3 is formed integral with the other end of the hook and is provided with a lateral extension 4, having an integral V-shaped arm 5 at its outer end. The free end of this arm is pointed, as shown at 6, and the apex 7 of the arm is preferably in position adjacent the head 2.

In using this device the end 6 is inserted through a garment at a desired point, and said pin is turned so as to bring the garment in position upon the hook 1. The dress-shield or other article to be fastened to the garment is then placed upon the arm 5 and brought into position upon the lateral extension 4. If desired, two or more fasteners such as herein

described may be used and one secured to each of the articles to be fastened together. The two V-shaped arms 5 are then placed into engagement with each other, so as to form connecting means between the two parts.

I do not desire to restrict myself to the form of device illustrated in Fig. 1 and herein described, for the reason that various modifications may be employed without departing from the spirit of the invention.

In Figs. 2, 3, and 4 I have shown modifications. In Fig. 2 the fastener is provided with a hook 8, having a head 9; but the strip 10 extends therefrom at an incline, and the lateral extension 11 is arranged on the side thereof opposite to that from which the hook 8 projects. Moreover, the inverted-V-shaped arm 12 has a lateral extension 13, which is preferably parallel with the arm 11 and is pointed, as shown. The construction shown in Fig. 3 comprises a headed hook 14, a strip 15, and a bowed lateral extension 16, having a hooked arm 17 at its outer end. In Fig. 4 the fastener has a substantially S-shaped hook 18, but in other respects is similar to the hook shown in Fig. 1.

The devices above described are all simple and inexpensive in construction, durable, and artistic, and form convenient means for securing dress-shields or other articles to a garment, for fastening a placket of a skirt, and for any other purposes for which a pin of this character would ordinarily be employed.

In the foregoing description I have shown the preferred forms of my invention; but I do not limit myself thereto, as I am aware that modifications may be made therein without departing from the spirit or sacrificing any of the advantages thereof, and I therefore reserve the right to make such changes as fairly fall within the scope of my invention.

Having thus described the invention, what is claimed as new is—

1. A fastener of the character described comprising a strip having a headed hook at one end, a lateral extension at the other end, an inverted-V-shaped arm integral with said extension, and a laterally-extending end to said arm normally parallel with the first-mentioned extension.

2. A garment-fastener comprising a strip having a headed hook at one end, a lateral extension at the other end and in the same plane with the hook, and an inverted-V-shaped arm integral with the extension and in the same plane therewith, the apex of said arm being spaced from the head but adjacent thereto.

In testimony whereof I affix my signature in presence of two witnesses.

BLANCHE M. BURR.
